UNITED STATES PATENT OFFICE.

FRANK H. SCHERBRING, OF ARCADIA, IOWA.

CORN-HUSKER.

1,146,285.

Specification of Letters Patent. Patented July 13, 1915.

Application filed December 19, 1914. Serial No. 878,122.

To all whom it may concern:

Be it known that I, FRANK H. SCHERBRING, a citizen of the United States, residing at Arcadia, in the county of Carroll and State of Iowa, have invented certain new and useful Improvements in Corn-Huskers, of which the following is a specification, reference being had to the accompanying drawings.

10 This invention relates to an improved corn husker, and has for its primary object to provide an improved device of this character embodying certain structural features whereby the husk ripping point or spur is 15 prevented from penetrating too deeply.

The invention has for an additional object to provide a corn husker which may be applied and used with equal facility upon either wrist, the device including a suitable 20 wrist band or strap and a metal plate riveted or otherwise secured upon the same and provided upon one end with an upwardly and inwardly curved overhanging spur or husking point, said end of the plate being 25 provided with an inwardly and downwardly curved lug or finger disposed below the plane of said point to permit the penetration of the point into the corn husk.

With the above and other objects in view, 30 my invention consists in the novel features of construction, combination, and arrangement of parts to be hereinafter more fully described, claimed, and illustrated in the accompanying drawing, in which,

35 Figure 1 is a perspective view showing my improved corn husker applied to the wrist of the operator; Fig. 2 is an enlarged plan view; Fig. 3 is an end elevation of the husking plate; and Fig. 4 is a section taken 40 on the line 4—4 of Fig. 2.

Referring in detail to the drawing, 5 designates a wrist band or strap of any suitable material, preferably leather. Upon one end of this wrist band, a plurality of buckles indicated at 6, are secured, and upon the opposite end of the band, a series of fastening straps 7 are secured for connection to the respective buckles. An additional buckle 8 is also secured upon the end of the strap 50 first referred to, by the same rivet or other fastening element which secures one of the buckles 6 thereon, said buckle 8, however, being disposed at right angles with respect to the buckle 6.

55 A metal plate 9 is secured upon the wrist band 5 by means of suitable rivets indicated

at 10, and this band is preferably slightly curved transversely, so that it will conform to the curvature of the wrist when the device is applied. One of the rivets 10 also 60 secures one end of a strap 11 to the band 5, the other end of which is adapted to be connected to the buckle 8, as shown. One end of the plate 9 is formed with an upwardly and inwardly curved portion indicated at 65 12, which terminates in a substantially triangular-shaped ripping point or spur 13, said spur extending over the plate 9 in substantially parallel relation thereto. The central portion of this spur and the curved 70 end 12 of the plate is cut out to provide a relatively small triangular-shaped spur or point 14 which is bent or curved inwardly and downwardly, the apex of said spur engaging upon the surface of the plate 9. It 75 will be observed that the top of this spur 14 is disposed below the bottom face of the husking point or spur 13.

In the use of the device, the band 5 is strapped upon the wrist of the operator, as 80 clearly shown in Fig. 1 of the drawing, the strap 11 being engaged over the thumb to prevent inward movement of the band upon the wrist from its applied position. The ear of corn, held in the other hand, is drawn 85 over and upon the inwardly projecting point 12 so that the same will rip the husk longitudinally, whereby the same is readily removable from the ear. The inwardly bent or curved point 14 limits this penetration 90 of the point 13, as will be readily understood, and prevents the corn kernels being removed from the ear. This point 14 also acts to spread the split portions of the corn husk and direct the same against the inner 95 concave face of the curved end 12 of the plate on opposite sides of said point, thus preventing the husk from passing through the opening in the curved end of the plate which is formed by cutting the point 14 out 100 of the same, and wedging therein.

From the foregoing description, taken in connection with the accompanying drawing, the construction, manner of operation, and several advantages of the invention will 105 be clearly and fully understood.

The device may be very easily and quickly applied to either wrist and greatly facilitates the husking of corn, whereby the operator is relieved of considerable labor incident thereto.

It will, of course, be obvious that the plate

9 and the husking point formed thereon may be made in various shapes and sizes.

The device is also susceptible of many other modifications in the form, proportion, and arrangement of the several parts, and I, therefore, reserve the privilege of resorting to all such legitimate changes as may be fairly embodied within the spirit and scope of the invention as claimed.

10 Having thus fully described my invention, what I desire to claim and secure by Letters Patent is:—

15 1. A corn husker comprising a metal plate provided upon one end with a returned centrally located husking point disposed above and in spaced relation to the body of the plate, said end of the plate being further provided with means spaced from the under side of said point to limit the penetration 20 of the point through the corn husk.

2. A corn husker comprising a metal plate having one of its ends inwardly bent or curved and terminating in a husking point disposed in spaced relation to the body of

the plate, said curved end of the plate being further provided with a central inwardly bent point disposed in spaced relation to the under side of said husking point to limit the penetration of the latter through 25 the corn husk.

30 3. A corn husker comprising a plate having an inwardly bent or curved end terminating in a husking point disposed in spaced relation to the body of the plate, said curved end of the plate and said husking point having a spur cut therefrom and bent inwardly and downwardly to contact at its point with the plate, the intermediate curved portion of 35 said spur being spaced from the end of the husking point to limit the penetration of 40 the latter through the husk.

In testimony whereof I hereunto affix my signature in the presence of two witnesses.

FRANK H. SCHERBRING.
